(57) **CLAIM**

I claim the ornamental design for a fitted cellular phone case, as shown and described.

DESCRIPTION

FIG. 1 shows an isometric front view of the invention with an environmental cellular phone inside the case to show conditions of use;

FIG. 2 shows an isometric front view of the invention without the environmental cellular phone.

FIG. 3 shows the straight front view of the invention.

FIG. 4 shows the straight back view of the invention.

FIG. 5 shows the straight left view of the invention.

FIG. 6 shows the straight right view of the invention.

FIG. 7 shows the straight top view of the invention; and,

FIG. 8 shows the straight bottom view of the invention. The broken lines depicting a cellular phone in FIG. 1 represents environmental subject matter which forms no part of the claimed design. The broken line clips and grommets on the rear and interior surfaces off the cellular phone case depict portions of the cellular phone case that form no part of the claimed design. The dark broken lines on the surface of the article, shown adjacent to the openings, and semas, represent stitching which forms a part of the claimed design.
